RUSSELL E. HANSEN, OF DETROIT, AND OTTO J. GROEHN, OF GROSSE POINTE PARK, MICHIGAN, ASSIGNORS TO HUDSON MOTOR CAR COMPANY, OF DETROIT, MICHIGAN, A CORPORATION OF MICHIGAN

APPARATUS FOR FORMING FLANGED OPENINGS IN SHEET-METAL PANELS AND THE LIKE

Application filed December 17, 1927. Serial No. 240,891.

This invention relates to apparatus for sizing and setting a flanged opening in a body of sheet metal and underturning the flange, and more particularly to apparatus for setting the window opening in a metal automobile body door panel.

It is an object of the invention to provide an apparatus which will perform these operations rapidly and efficiently.

10 Before explaining the invention in detail it is desired to point out that the embodiment herein described is merely for the purpose of illustration and that the invention is not thereby limited except as pointed out by the 15 claims appended hereto.

The invention will be more clearly understood from the following description taken in conjunction with the accompanying drawings, in which

20 Figs. 1 and 2 are elevational views of a door panel before and after being shaped respectively in accordance with the invention.

Figs. 3 and 4 are sectional elevational views taken upon the lines 3—3 of Fig. 1 and the 25 lines 4—4 of Fig. 2, respectively.

Fig. 5 is a sectional view of an apparatus embodying the invention taken upon the line 5—5 of Fig. 8 showing the upper and lower dies separated.

30 Figs. 6 and 7 are similar sectional views showing the relation of the parts at the beginning and completion of the forming operations respectively.

Fig. 8 is a sectional plan view taken upon 35 the line 8—8 of Fig. 5.

The embodiment of the invention illustrated comprises a base 10 provided with projections 11 at its outer edges forming a depression 12. A block 13 projecting upwardly from the base and positioned in the central part of the depression is suitably secured to the base as by bolts 14. A support 16 is provided with an opening 9 permitting movement toward and from the block 13 and 40 is guided in its movement by guides 17 suitably secured thereto and slidably engaging openings 18 in the base. The support 16, preferably, is held yieldingly in raised position by springs 20 extending between openings 21 and 22 in the support and base re-

spectively. The upward movement of the support 16 is limited by bolts 23 secured thereto and passing through openings 24 in the base provided with a shoulder 25 serving as a stop to engage the head of the bolts.

The lower outer die members 30 are movably carried upon the support 16 and each is provided at its lower outer surface with a wearing block 31 adapted to engage a suitably shaped cam 32 positioned upon the inner upper surface of each of the projections 11. The inner upper surface of the die member 30 is provided with a wearing block 33 suitably shaped for engagement with the flange and body of the sheet metal panel. 65 Each die member 30 is held normally in engagement with a cam 32 by springs 34, positioned in slots 35 with one end engaging the end of the slot and the opposite end engaging a pin 36 secured in the die members 30 and 70 projecting downwardly within the slot 35.

An inner die member comprises four corner portions 40 slidably mounted on the support 16 and guided by bolts 4 passing through elongated slots 5 therein and threaded into the support 16. The upper outer portion of each corner member 40 is provided with a wearing block 45 secured thereto in any suitable manner as by screws 46. Adjacent corner members are connected by 80 a member 41 movable relative thereto and secured thereto by screws 42 passing through elongated slots 43 in the member 41 and engaging the corner members. The inner surface of each corner member 40 is provided 85 with a wearing block 47 secured thereto in any suitable manner as by screws 50 and adapted for cooperative engagement with cams 48 secured upon the upper corner portions of the block 13. The corner portions 90 40 of the inner lower die members normally are held in engagement with the cams 48 by springs 51 positioned with one end against the end of a slot 52 in the support 16 and with the opposite end engaging a pin 53 secured in the corner portions 40 and extending 95 downwardly into the slots.

An upper die member 55 is suitably mounted upon a reciprocable ram and is shaped to engage the body of a sheet metal panel 100

57 placed upon the lower outer die member 30 and to pass within the opening of the panel and engage the flange 58 thereof and the top surface of the inner die members. 5 The upper die member 55 is suitably guided in its movement towards the lower die members by guides 60 secured thereto and adapted for slidable engagement in guideways 61 in the block 13.

10 In operation, a body of sheet metal such as a sheet metal door panel 57 of the type shown in Figs. 1 and 2 having a flange 58 determining the outer end of a window opening is placed upon the wearing blocks 33 of the 15 outer lower die members with the flange 58 surrounding the inner die members. The upper die member 55 is then moved downwardly to engage the panel upon the outer lower die members and move the latter downwardly together with the support 16. During this downward movement the wearing blocks 31 engage the cams 32 which direct the outer lower die members 30 inwardly along the top surface of the support 16 so 25 as to bring the wearing blocks 33 into engagement with the flange 58. At the same time the upper die member is passed into the window opening to engage the opposite side of the flange 58 and press the same 30 against the wearing blocks 33 of the outer lower die members 30 thereby sizing and setting the window opening. Upon further downward movement, the upper die member 55 engages the corner portions of the inner 35 lower die members causing the same to move downwardly together with the support 16 thereby bringing the wearing blocks 47 into engagement with the cams 48 causing the corner portions of the lower inner die members 40 to move outwardly toward the corners of the window opening and turn the depending portion of the flange 58 under the lower surface of the wearing blocks 33 on the outer lower die members.

45 What we claim is:

1. In an apparatus for shaping a flanged opening in a sheet metal body, the combination of a lower die including inner and outer die members, an independently mounted upper die adapted to move in a predetermined path into said opening, means for moving said inner die member to turn the flange of said opening under said outer member, and means causing said outer die member there- 50 after to move away from the work.

60 2. In an apparatus for shaping a flanged opening in a sheet metal body, the combination of a lower die including inner and outer die members, an upper die adapted to move into said opening and move said inner die member, means for directing the movement of said inner member outwardly to turn the flange of said opening under said outer die member, and means for thereafter causing 65 said outer die member to move away from

the work when said upper member is removed therefrom.

3. In an apparatus for shaping a flanged opening in a sheet metal body, the combination of a lower die including inner and outer die members, an upper die adapted to move into said opening and move said inner and outer die members, means for directing the movement of said outer die member inwardly against the flange of said opening and the movement of said inner member outwardly to turn the flange of said opening under said outer member, and means for causing the outer member thereafter to move away from the work when said upper member is removed therefrom. 70 75 80

4. In an apparatus for shaping a flanged opening in a sheet metal body, the combination of a lower die including a yieldable support carrying an outer die member and a 85 slidable inner die member, an upper die adapted to move into the opening and move said inner die member, a cam for directing the movement of the inner member outwardly to turn the flange of said opening under the 90 outer member, and means for moving said outer member outwardly away from the underturned flange.

5. In an apparatus for shaping a flanged opening in a sheet metal body, the combination of a lower die including a yieldable support having inner and outer die members slidably mounted thereon, an upper die adapted to move into said opening and move said inner and outer die members with said support, fixed cams arranged first to direct said outer die members inwardly along said yieldable support and against said flange member and thereafter move said inner member outwardly along said yieldable support to turn said flange under said outer die member, and means for moving said inner and outer die members thereafter away from the work. 95 100 105

6. In an apparatus for shaping a flanged opening in a sheet metal body, the combination of a lower die including a yieldable support having inner and outer die members slidably mounted thereon, an upper die adapted to move into said opening and move said inner and outer die members with said support, fixed cams arranged first to direct said outer die members inwardly along said yieldable support and against said flange and thereafter move said inner member outwardly along said yieldable support to turn said flange under said outer die member, and means for moving said inner and outer die members thereafter away from the work, including a spring arranged to resist the inward and outward movements of said outer and inner members and return the same when said upper die is withdrawn from said opening. 110 115 120 125

7. In an apparatus for shaping a flanged opening in a sheet metal body, the combination 130

tion of a lower die including inner and outer die members, an upper die adapted to move in a predetermined path into said opening to shape the same against said outer die member, said inner die member being composed of corner portions and relatively movable connecting portions, means for moving the corner portions of said inner die member outwardly toward the corners of said flange to 5 turn said flange under the outer die member, and means for moving said inner and outer die members thereafter away from the work.

8. In an apparatus for shaping a flanged opening in a sheet metal body, the combination of a lower die including a yieldable support having inner and outer die members slidably mounted thereon, an upper die adapted to move into said opening and move said inner and outer die members with said support, said inner die member being composed of corner portions and relatively movable connecting portions, fixed cams arranged to direct said outer die members inwardly along said yieldable support and against the flange 15 20 and thereafter direct the corner portions of said inner members outwardly along said yieldable support toward the corners of said flange to turn said flange under said outer die member, and means for moving said inner 25 and outer die members thereafter away from the work.

9. In an apparatus for shaping a flanged opening in a sheet metal body, the combination of a lower die including inner and outer 30 die members, an upper die adapted to move in a predetermined path into said opening to draw and shape the same against said outer die member, means for moving said inner die member to turn the flange of said opening 35 40 under said outer member and means for causing said outer member thereafter to move away from the work.

In testimony whereof we affix our signatures.
